New York, N. Y., a corporation of New
York

Application December 12, 1935, Serial No. 54,019

6 Claims. (Cl. 235—61.7)

This invention relates to improvements in multiplying machines and more particularly to machines of the record card controlled type.

The principal object of the invention is to provide mechanism for reducing the necessary operations involved in the multiplication of two factors to a minimum.

A more specific object is to provide mechanism for sensing the magnitude of the factors to be multiplied and selecting the one having the lesser number of significant digits as the multiplier. In the type of multiplying machine to which the invention is applied, a number of multiplying cycles is performed which is equal to the number 10 of significant digits in the multiplier factor regardless of the size of the multiplicand. For example, with a multiplicand of 205 and a multiplier of 67423, five multiplying cycles are required in present machines. In accordance with the 20 present invention, the number 205 is automatically selected to be the multiplier whereby the number of multiplying cycles is reduced to two with a consequent reduction of wear and saving in the time required to perform the multiplying 25 operations.

The machine is provided with two accumulators generally called the "Multiplier entry device" and the "Multiplicand entry device" and it is an object of the invention to sense the factors perforated on a record card and automatically enter the lesser factor into the "Multiplier entry device". The factors appear in two fields of a record card and each field is normally connected to one of the entry devices.

If the field connected to the "Multiplier entry device" is found to have the greater number of significant digits, the connections are reversed and such factor is entered into the "Multiplicand entry device". If the factors both have the same 40 number of significant digits, the connections remain undisturbed even if the multiplier factor has a greater value.

Various other objects and advantages of the 45 invention will be obvious from the following particular description of one form of mechanism embodying the invention or from an inspection of the accompanying drawings; and the invention also constitutes certain new and useful features of construction and combination of parts hereinafter set forth and claimed.

In the drawings:

Figs. 1a, 1b, and 1c taken together and placed one above the other in the order named constitute a complete wiring diagram of the electric

circuits of the multiplying machine provided with the features of the present invention.

Fig. 2 is a cross-sectional view of the record card feeding and analyzing mechanism of the 5 machine.

Fig. 3 is a specimen of a record card showing the manner in which the two factors are perforated in separate fields.

Fig. 4 is a timing diagram of the electrical 10 devices of the machine.

The machine to which the invention has been applied will first be briefly described and reference may be made to my Patent No. 1,933,714, granted November 7, 1933, for the specific 15 details of construction and operation. Record cards R, such as shown in Fig. 3, which have two fields such as are labelled "Quantity" and "Price" are placed in the supply hopper 10 of the machine (Fig. 2). From here a picker 11 will advance the cards, one by one, from the bottom of the stack to feed rollers 12 which feed the card to pass a row of brushes 13 and a single brush 14. The card is further advanced by and around a contact drum 15 to pass a row of analyzing brushes 16 which sense and control the entry of 20 the factors into the multiplier and multiplicand entry receiving devices. The card then proceeds into the punching unit of the machine where, later, the computed product is punched back in 25 the card as indicated in Fig. 3.

While multiplying operations proceed in accordance with the factors on a card the next following card will have been advanced to a position wherein the row of index point positions in which zeros occur lies beneath the row of brushes 30 13 and it is through these brushes that the lesser factor is determined before the card is advanced to pass the brushes 16 as will be described later. The cards are advanced with the "9" index point 35 positions leading and when the feed mechanism comes to rest, the leading margin will be under brushes 16, the row of "0" index point positions will be at the row of brushes 13 and the row of "X" index point positions will be under the brush 14.

Closure of the main line switch SW (Fig. 1c) places the motor M' in operation which motor drives the AC-DC generator so labelled (Figs. 1a and 1c) to supply direct current to DC lines 40 17 and 18, and alternating current to ground and 45 to a line 19 (Fig. 1a).

The start key contacts 20 (Fig. 1c) are now closed by depression of the start key button which completes a circuit from the DC line 18, through a relay coil C, contacts 20, now closed, 50

- upper contacts G1, cam contacts FC2 to line 17. The coil C establishes a holding circuit through its contacts C2 and cam contacts FC8. The coil C, when energized, also closes a pair of contacts C1 (shown in the upper part of Fig. 1c) which will complete a circuit from line 18, normally closed contacts F1, card feed clutch magnet 21, cam contacts FC6, stop key contacts 22, contacts C1, punch feed rack contacts P1, to line 17.
- 10 Energization of clutch magnet 21 will cause withdrawal of a card from the supply magazine 10 (Fig. 2) and will advance it to the analyzing brushes 13 and then to the brushes 16 to a position where the leading edge is just under the brushes 16. During the movement of the card, the card lever is engaged to close card lever contacts 24 (Fig. 1c) which complete a circuit from line 17, contacts 24, relay magnet H to line 18. In starting up the machine, it is necessary to hold 20 down the start key to maintain contacts 20 closed during the first complete card feeding operation, or, alternatively, to depress the start key a second time. At the beginning of the second card feed cycle, the closure of cam contacts FC11 will 25 energize relay magnet G through a circuit including the card lever contacts 24.

Relay magnet G will close its normally open contacts G1, setting up a holding circuit through cam contacts FC2 and will also close contacts G2 to provide a further holding circuit through the card lever contacts 24. These two holding circuits alternate in maintaining relay magnet G energized as long as cards continue to feed from the magazine.

35 The relay magnet H is also provided with a holding circuit which extends through card lever contacts 24 or serially through relay contacts G2 and cam contacts FC2. The relay contacts H1 (Fig. 1a) are shifted to the reverse of the position shown in this figure, thereby supplying current to the impulse distributor 25. The circuit extends from the AC generator through line 19 to the now closed contacts H1, cam contacts FC7, distributor 25, contact drum 15, from which circuits will be completed through the analyzing brushes 16 to effect entries into the accumulator magnets 26MC and 26MP representing the multiplicand and multiplier accumulators respectively. These circuits extend from the sockets 26 of brushes 16 through plug connections 27 to sockets 28 and thence through normally closed relay contacts 29a to magnets 26MC and 26MP.

As shown in Fig. 1a, the four brushes 16 to the left which sense the "Quantity" field of the card 55 R are thus normally connected to the magnets 26MC and the four brushes 16 to the right which sense the "Price" field of the card are normally connected to the magnets 26MP. According to the present invention as will be set forth herein-after, the relay magnet 29 is energized when the value sensed by the right hand set of brushes 16 has a greater number of significant digits than the value sensed by the left hand set of brushes 16. The resulting shifting of relay contacts 29a will 65 reverse the connections so that through wires 30, the left hand set of brushes will control the entry into the magnets 26MP and the right hand set of brushes will control the entry into the magnets 26MC, thus establishing the value having the 70 lesser number of significant digits as the multiplier.

After the first card has traversed the brushes 16 it continues into the tray of the punching unit, and upon its arrival there, it causes closure of 75 punch card lever contacts 31 (Figs. 2 and 1c)

which cause energization of relay magnet F. With relay magnet F energized, its contacts F1 will be shifted from the position shown, thus interrupting the circuit to the card feed clutch magnet 21 to suspend card feeding. The closure of normally open contacts F1 establishes a circuit from line 18, now closed contacts F1, cam contacts CC2, trip magnet 32 of the punching unit to call the clutch mechanism of such unit into operation to advance the card therein, the circuit continuing through eject contacts P3 and relay contacts K1 which at this time are in position reverse to that shown.

The contacts K1 are controlled by relay magnet K which is energized through contacts 34 in the punching unit. These are the so-called "last card column" contacts, closed whenever the card advancing carriage of the punching unit is in last column punching position, which position it occupies when the operation of the entire machine is first started so that upon starting, relay magnet K is energized and its contacts K1 are in shifted position. The cards are handled in the card punching unit in the customary manner as set forth in my above mentioned Patent No. 1,933,714.

As the analyzed card is advanced to the punching mechanism, a circuit is completed upon closure of cam contacts CC2 (Fig. 1a) from line 18, contacts CC2, contacts K2, (now closed) contacts L2, contacts F2 (now closed) to magnet 35LH and thence to ground. Magnet 35LH causes resetting of the so-called LH accumulator which receives the left hand components of the partial products as will be explained later. During the resetting 35 operation contacts 36 and 37 (Fig. 1c) are closed, establishing a circuit from line 17, upper contacts 36, contacts 37, wire 38 (Figs. 1b and 1a), relay magnet M, wire 39 to line 18. A further circuit branches from wire 38 (Fig. 1c) through relay 40 magnet L to line 18 and the consequent closure of contacts L1 will provide a holding circuit from line 17, wire 40, punch feed rack contact 41, wire 42, contacts L1, magnet L to line 18, branching also through wire 38, relay magnet M, wire 39, 45 to line 18. Relay magnet M closes its contacts M2 to provide a further holding circuit for the relays, extending from line 18, wire 39, relay M, contacts M2, wire 43 (Figs. 1b and 1c) to the normally closed contacts 44 and thence to line 17. 50 Contacts 44 are open during the subsequent operation wherein the MC accumulator is reset and until such time, relay magnet M will remain energized.

Magnet M is the so-called master relay magnet 55 of cycle controlling unit and it calls the cycle controller into operation to determine the location of the significant figures in the multiplier. The circuit through the wire 38 also extends to the zero segments of the MPRO readout. If any of 60 the brushes of this MPRO readout stand at zero, selected ones of the magnets Yu, Yt, etc., will be energized according to which denominational orders of the multiplier contain zeros.

The magnets Yu, Yt, etc. control contacts 65 Yu-a, Yt-2, etc. through which circuits are completed to the column shift relay magnets CSu, CSt, etc. and to the multiplying relay magnets 47. In those positions in which the multiplier digit is zero, the associated magnet Yu, Yt, etc. will be energized and the related contacts Yu-2, Yt-2, etc. will be shifted from the position shown in the diagram so that the related magnet CSu, CSt, etc. will be disconnected from the circuit which is traceable from line 18, cam 75

contacts CC2, relay contacts M1, normally closed contacts Yu—2, relay magnet CSu, through the appropriate readout spot in one order of the readout section MPRO to the corresponding relay magnet 47 and thence to ground. Where the units order of the multiplier is "5", this circuit is completed through the "5" commutator segment in the units order of the MPRO. The function of the contacts Yu—2, Yt—2, etc. is to direct the multiplying relay selecting circuit through only those positions in which significant figures occur and to skip the positions in which zeros occur. With magnet 47 energized (for example the X5 magnet 41), the related contacts shown in the center of Fig. 1a will become closed and with the emitter 48 in operation, impulses will be emitted through the contacts of the times 5 multiplier, through the MCRO readout and thence through the column shift relay contacts CSL and CSR shown at the top of Fig. 1b and partial product entries will be directed into the LH and RH accumulators accordingly. The CSL and CSR relay contacts are controlled by the relay magnets CSu, CSt, etc. and serve to effect the proper denominational allocation of the partial products entries. Thus, when multiplying is being effected by the units digit of the multiplier, the units magnet CSu is energized and the units set of contacts CSL and CSR are closed.

30 Energization of a relay magnet CSu, CSt, etc. will also close a pair of contacts CSu—3, CSt—3, etc. (Fig. 1a) which will cause energization of the relay magnet Yu, Yt, etc. in the order in which multiplying is taking place. This in turn 35 will shift the related pair of contacts 45a so that when cam contacts CC2 again close, the afore-traced circuit will be directed through the magnet CSu, CSt, etc. in the order containing the next higher significant figure and will skip the 40 magnets CSu, CSt, etc. in positions in which zeros are present.

The machine continues multiplying operations during which the partial products are entered in succession into the LH and RH accumulators. 45 After a multiplying cycle has been effected for each significant multiplier digit, all of the magnets Yu, Yt, etc. will have been energized and all of the contacts Yu—2, Yt—2 will be in their shifted positions so that on the next following 50 cycle, the closure of cam contacts CC2 will complete the circuit which extends through all of the now closed contacts Yu—2, Yt—2 to the relay magnet 49 and reset magnet 50MC. A parallel circuit also extends through cam contacts 55 PC10 and reset magnets 50MP. The latter magnets connect the MC and MP accumulators for resetting operations which take place during the next cycle to zeroize these accumulators.

Relay magnet 49 closes its contacts 49a (Fig. 60 1b) to connect the readout section RHRO to the entering magnets 26LH of the LH accumulator to permit the transfer of the sum of the right hand partial products into the LH accumulator to produce the complete product.

65 The circuits involved in this transferring operation extend from the emitter 48 (Fig. 1a) through a group of wires 51 (Fig. 1b) to the RHRO readout device from whence the circuits will continue through contacts 49a to adding 70 magnets 26LH. During this cycle in which the MC and MP accumulators are reset concurrently with the RH to LH transfer operation, the normally closed contacts 44 (Fig. 1c) which are operated by a cam on the MC reset shaft, will 75 open to interrupt the circuit to the cycle con-

trolling relay magnets Yu, Yt, etc., thus causing deenergization of all these magnets and the interruption of their related contacts.

When the contacts 44 are shifted from the position shown in Fig. 1c, a circuit is completed through relay magnet D which sets up a holding circuit through its contacts D2 and cam contacts CC1. The relay magnet D also closes a pair of relay contacts D1 which serves to connect the emitter 52 to line 19 so that during the next cycle 10 impulses are emitted therethrough to the LHRO readout section and circuits are completed to the plug sockets 53 from whence, through suitable plug connections such as 54 to sockets 55, the amount standing in the LHRO section will be 15 entered in magnets 26SP of the summary products accumulator.

During the RH to LH transfer cycle, closure of a pair of contacts 49b (Fig. 1a) permits the completion of a circuit near the end of the cycle 20 extending from emitter 48 through relay contacts 49b and reset magnets 50RH to effect resetting of the RH accumulator. Also during the cycle in which the MC accumulator is reset, contacts 56 (Fig. 1c) are closed to complete a circuit through relay magnet C whose contacts hold the circuit through cam contacts FC8.

Contacts C1 are also closed at this time to energize the card feed clutch magnet 21 to feed the next card to pass the analyzing brushes 16 30 and during such passage the factors are entered into the appropriate MC and MP accumulators.

Closure of cam contacts FC4, due to operation of the card feed mechanism, will complete a circuit through relay magnet B which closes its 35 contacts B2 to provide a holding circuit through contacts 36. Magnet B controls the punching operation which takes place concurrently with card feeding. The detailed operation of the punching mechanism is set forth in the patent referred 40 to and the same will be but briefly described herein to explain the circuits involved in the operation.

Energization of relay magnet B effects closure of its associated contacts B1 (Fig. 1c) which 45 complete a circuit from line 17, through contacts B1, normally closed contacts 57, switch 58, wire 59 (Fig. 1b) to the common strip 60 of the column selector of the punching unit. As the punched card carriage advances, the brush 61 connects the strip 60 to segments 62 in succession as corresponding columns of the record card are in punching position. From the segments 62 which are connected to plug sockets 63 connections 64 are made to the readout sockets 65 55 of the LHRO readout device in the orders in which it is desired to have the product punched. The circuits continue through the wires 66 to punch selecting magnets 67 and thence to line 18. Energization of any magnet 67 will cause closure of a pair of contacts 68 (Fig. 1c) to complete a circuit to the punch magnet 69 which effects a perforation in the appropriate index point position of the card column and also effects an operation of the escapement mechanism to 65 advance the card to the next column to receive punching.

After all the selected columns have been perforated in accordance with the controlling product, the card carriage escapes to the so-called 70 last column position in which contacts 34 are closed, energizing relay magnet K. This relay closes its contacts K2 to effect resetting of the LH accumulator and also shifts its contacts K1 to energize the eject magnet 85 (Fig. 1c) to eject 75

the punched card, following which trip magnet 32 is energized to advance the next card to the punches.

The foregoing described briefly the general 5 operation of a commercial multiplying punch whose sequence of operations may be summarized as follows:

- First cycle — Advance card, enter factors, punch product on preceding 10 card,
 10 Reset RH accumulator
 Second cycle — Advance card to punch carriage
 Third cycle — Reset LH accumulator
 15 Fourth cycle — Multiply This number of cycles is equal to the number of significant digits in the multiplier
 Fifth cycle — Multiply
 Sixth cycle — Multiply
 20 Seventh cycle — Reset MP and MC accumulators, transfer RH to LH.

20 The improvements of the present invention will now be set forth and the operation of this mechanism takes place during the card feeding cycles for which the timing of the electrical devices is shown in Fig. 4.

25 The brushes 13 which sense the zero index point position of the card fields containing the factors are connected to plug sockets 70 from which plug connections 71 are made to sockets 72 which are connected to segments of emitters 73 and 74.

30 Eight brushes 13 are provided for each factor and where all eight columns of the card are used the eight sockets 72 of each emitter are 35 plug connected. The brushes of the emitters 73, 74 are in constant rotation and they engage their respective segments as indicated on the timing diagram. Near the end of the card feeding operation, as a card comes to rest with its 40 zero index point positions beneath brushes 13, cam contacts FC17 close, causing energization of relay magnet Z which in turn closes its contacts Z1 to provide a holding circuit through 45 cam contacts CC5. This circuit is maintained during the next cycle throughout the period that the emitter brushes make contact with their segments and is then opened. The magnet Z also closes its contacts Z2 and Z3 so that circuits may be completed to stepping magnets 50 75, 76. If a zero is present in the column connected to the "9" emitter segment, a circuit will be completed which is traceable from line 55 17, cam contacts FC5, brush common, zero hole in the card, brush 13, socket 70, connection 71, socket 72, "9" emitter segment, contacts Z2 or Z3, magnets 75 or 76 to line 18. When the emitter brush has advanced to the "8" segment, the circuit will be again completed if a zero is present in the associated column and magnet 60 75 or 76 will again be energized. Thus, for each zero sensed by brushes 13, a magnet 75 or 76 will receive one impulse.

65 The magnets 75 and 76 control so-called stepping or counting relays and each energization will actuate a pawl and lever 77 to advance a ratchet 78 one step or tooth. Integral with one of the ratchets 78 is a brush 79 which progressively contacts with fixed commutator segments 80 and integral with the other ratchet is a group of electrically connected brushes 81 which contact 70 with fixed commutator segments 82.

75 The segments 80 and 82 are interconnected by wires 83 as shown and control the energization of relay magnet 29 in such manner that the magnet becomes energized when the factor sensed

by the brush 79 has advanced more steps than the brushes 81 and remains deenergized when the brush 79 has advanced the same number of or fewer steps than the brushes 81.

80 The operation of the device may best be explained by reference to particular examples. Let it first be assumed that neither factor contains zero. Neither magnet 75 nor 76 will be energized and the brushes 79, 81 remain in the positions shown. During the next following card 10 feeding cycle as the presensed card is advanced to the brushes 16, cam contacts FC16 close and complete a connection from line 17 to brushes 81 and wires 83. Since none of the segments 80 is in contact with brush 79 no circuit is completed to magnet 29. If brush 79 had been advanced one step to contact the first segment 80, the circuit would be completed through the lowermost wire 83, first segment 80, brush 79, magnet 29, to line 18. This circuit is continued 20 by contacts FC16 as the card passes the sensing brushes 16 and since contacts 29a (Fig. 1a) are shifted by the energization of magnet 29 the factors are entered reversely into the multiplier and multiplier receiving accumulators. 25

25 Consider now the amounts shown in the card of Fig. 3 with the brushes 13 labelled "Quantity" and "Price" sensing the zero index point positions of the similarly designated card fields.

30 The "Price" field is normally arranged to enter 30 into the MP accumulator and the "Quantity" field into the MC accumulator so that the "Price" would ordinarily control the number of multiplying cycles which would be five for the value 67423. It may be mentioned here that for certain types 35 of work the field set aside to receive items of a designated kind are filled out with zeros to the left of the first significant figure and these are also sensed by the brushes 13.

35 Thus for the "Price" 67423, punched in the 40 eight-column field as 00067423, the related magnet 75 is energized three times and for the "Quantity" 205, punched in the other eight-column field as 00000205, the related magnet 76 is energized six times, so positioning the brushes 79 and 81 45 that the subsequently completed circuit for energizing magnet 29 will be completed through the third wire 83 from the top (emphasized by a heavy line), the brush 79 in contact with the sixth segment 80 and the third brush 81 from the 50 left which is now in contact with the segment 82 at the terminal of the heavy-line wire 83. Consequently the entering connections are reversed and the "Quantity" value 205 is entered as the 55 multiplier.

60 In the example of Fig. 3, the amounts in fields which control the reversing magnet 29 are also entered into the MP and MC accumulators but it will be appreciated that the fields from which entries are so made may be two different fields. 60 Thus, one pair of fields may determine whether connections for another pair of fields are to be reversed or not, or by omitting one set of entering connections such as those to the MC accumulator, the device will determine simply whether the 65 amount in one field is to be entered or not entered.

65 In cases where the same number of card columns are not allotted to the two factors it is necessary to effect further plug connections 81 70 between sockets 80 (Fig. 1c) and sockets 72 so that the same number of sockets 72 are connected for each factor. The reason for this arrangement will be apparent if for example it be considered that a two column field designates 75

"Quantity" and a three column field designates "Price." Thus with a "Quantity" of 25 and a "Price" of 425, if only these five columns were connected to their respective emitters 14 and 18, no impulses would be transmitted to either magnet 16 or 15 and the "Price" would remain connected to the MP accumulator. If a plug connection 87 is made between a socket 86 and the "7" socket 12, the magnet 16 will receive one impulse through a circuit extending from line 17, cam contacts FC5, socket 86, connection 81, "7" socket 12, relay contacts Z3, magnet 16 to line 18 and the connections would accordingly be reversed to enter the "Quantity" 25 as the multiplier.

During the cycle following the one in which the factors are read from the card, cam contacts FC15 close during the period indicated in Fig. 4 to complete a circuit from line 17, contacts FC15, and resetting magnets 90 of the stepping relays, to line 18. The magnets in the usual manner move the stepping pawls out of engagement with the ratchets 18 so that they may be returned to starting position by the usual springs (not shown).

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a record controlled multiplying machine, means for feeding a record card having a pair of fields, each field comprising a plurality of columns and each column containing a perforation representing a digit or zero, means for sensing the perforations in said fields, entry receiving devices controlled thereby, connections between said sensing means and said devices, further sensing means and means controlled thereby for counting the number of zero representing perforations in each field and means controlled by said counting means for modifying the connections between said first named sensing means and said entry receiving devices.

2. In a machine of the class described, means for sensing a multi-columnar field of a record card for designations representing an amount, means for sensing a second multi-columnar field of said record card for designations representing another amount, each column of said fields containing a designation representing either a significant digit or zero and each field containing the same number of columns, an entry receiving device, alternative connections between said device and both of said sensing means, further sensing means responsive to certain of the designations, means controlled thereby for ascertaining the relative numbers of significant digits represented in the two fields and means controlled by said ascertaining means for rendering said alternative connections effective to connect the

sensing means related to the field having the lesser number of significant digits to said entry receiving device.

3. In a record controlled multiplying machine, a pair of entry receiving devices, entering means for each, means for analyzing a pair of fields of a record card for perforations representing two factors, means normally connecting the entering means of one device with the analyzing means of one of said fields, means normally connecting the entering means of the second device with the analyzing means of the second field, further analyzing means, means controlled thereby for counting the number of zeros present in each factor and means controlled by said last means for causing a reversal of said connecting means to connect the entering means of the first device to the analyzing means of the second field and the entering means of the second device to the analyzing means of the first field.

4. In a multiplying machine, a presensing means, a main sensing means, means for advancing a record card to both said means in succession, said card having two fields of the same number of columns and each column containing a designation representing a significant digit or zero, means controlled by said presensing means for ascertaining the relative numbers of significant digits represented in the two fields, an entry receiving device, connections between said device and said main sensing means normally connecting the same, and means controlled by said ascertaining means when a predetermined one of said fields contains a greater number of significant digits for operating said connecting means to disconnect said device from said sensing means.

5. In a multiplying machine, a presensing means, a main sensing means, means for advancing a record card to both said means in succession, said card having two fields of the same number of columns and each column containing a designation representing a significant digit or zero, means controlled by said presensing means in response to the sensing of zero representing designations for counting the number of zero designations in each of said fields, an entry receiving device, connections between said device and said main sensing means normally connecting the same, and means controlled by said counting means when a predetermined one of said fields contains a greater number of zero designations for interrupting said connections to disconnect said device from said main sensing means.

6. The invention set forth in claim 5 in which said advancing means is arranged to bring the card to rest at said presensing means for sensing of the zero designations while at rest and to move the card to pass the main sensing means for analysis of all digit representing designations while in motion and in which the means controlled by the counting means is arranged to maintain said connections interrupted while the card passes said main sensing means.

JAMES M. CUNNINGHAM.
